[57] CLAIM

The ornamental design for vehicle-wheel front face, as shown and described.

DESCRIPTION

FIG. 1 is a perspective view of a vehicle-wheel front face according to my new design;

FIG. 2 is an enlarged front elevational view thereof;

FIG. 3 is an enlarged side elevational view thereof; and, FIG. 4 is a front elevational view of a vehicle-wheel front face showing a second embodiment of my new design which lacks the central cover plate shown in the other figures, it being understood that the contour of the front face of the second embodiment is the same as the first embodiment as best shown in FIGS. 1 and 3 of the drawings except that the central hub area is flat.

Portions of the wheel depicted in broken line are for illustrative purposes only, and form no part of the claimed design.
